UNITED STATES PATENT OFFICE.

EDGAR B. HOOVER, OF SPOKANE, WASHINGTON.

COOLING SYSTEM.

Application filed January 11, 1924. Serial No. 685,713.

To all whom it may concern:

Be it known that I, EDGAR B. HOOVER, a citizen of the United States, residing at Spokane, in Spokane County, and State of Washington, have invented certain new and useful Improvements in Cooling Systems, of which the following is a specification.

My present invention relates to improvements in cooling systems for automobiles in which the internal combustion engine is cooled by the circulation of water in jackets around the cylinders of the engine for the purpose of extracting heat therefrom. Some well known types of circulation systems act on the principle that hot water seeks a higher level than cold water causing the water to flow from the lower radiator outlet pipe up through the water jackets, into the upper radiator water tank and down through the tubes of the radiator to the lower tank, to repeat the process. In many instances this system has been found inadequate for the purpose of cooling the engine, especially in warm weather. The primary object of my invention is the provision of means applicable for use in connection with existing systems of the above named type, and operated from the fan shaft of the cooling system, for positively causing circulation of the water to insure the necessary working conditions of the engine with respect to heat.

With this object in view the invention consists in certain novel combinations and arrangements of parts forming a pumping system, as will be hereinafter more fully pointed out and claimed. In the accompanying drawings I have illustrated one complete example of the physical embodiment of my invention wherein the parts are combined and arranged in accordance with the best mode I have thus far devised for the practical application of the principles of my invention.

Figure 1 is a view in side elevation of so much of an internal combustion engine or motor as is necessary to illustrate the application thereto of my invention.

Figure 2 is an enlarged sectional view of the water pipe connection between the radiator and cylinder head of the engine for conveying water to the former, and showing my screw pump therein with operative connections.

Figure 3 is a perspective view of a friction cone-wheel that is combined for use

with the fan-belt pulley for operating the pump.

For the purpose of identifying and disclosing the relationship of parts I have designated the engine cylinder head as 1 and the curved pipe connection between the cylinder head and radiator (not shown) as 2, and the water jacket for the cylinders as 3, through which the water circulates for cooling purposes. The fan 4, shaft 5, pulley 6 and driving belt 7 therefor are of well known or standard construction and the belt receives power from a suitable source as usual for transmission to the pulley 6. Power is supplied from this pulley for operating the pump of my invention through the use of a cone shaped friction wheel 8 which has spaced lugs 9 at its large edge that are capable of being bent over to engage the edge of the grooved pulley 6 to form a rigid structure to revolve therewith and drive the pump.

Within the connection pipe 2 and vertically arranged therein I provide a screw impeller or spiral pump blade 10 integral with its hub-sleeve 11 and the latter is fixed to revolve with the vertically disposed pump shaft 12 which extends upwardly from below into the interior of the pipe connection 2 as shown in Figure 2. The pump shaft is provided with a long bearing sleeve 13 seated in the hollow interior boss 14 of the pipe 2, and at the top of the boss a fixed retaining collar 15 is provided for the shaft and screw impeller. The shaft projects upwardly within the pipe 2 at its longitudinal axis and is provided with a bearing in the cross bar 16 extending transversely of the pipe 2 with its ends turned down as at 16' exterior of the pipe to form a close water tight joint in the pipe. A cone bearing or journal at the end of the shaft insures a stable rotation of the screw impeller, in addition to the long bearing sleeve in the boss 14.

At the lower end of the boss 14 which projects beneath the lower end of the pipe 2 a hollow packing nut 18 is connected to form an oil or lubricating chamber and suitable packing, together with a compressing washer 19, are located in the packing nut. Hard oil may be introduced into the packing nut and the shaft may be lubricated therefrom through the longitudinally extending groove 20 in the exterior surface of the shaft within its sleeve 13.

At the lower end of the shaft and exterior of the pipe 2 I affix a driven wheel 21 of suitable type having a friction rim 22 of rubber or other similar material for contact with the cone shaped friction pulley 8 on the fan-belt pulley 6.

It will be apparent that as the shaft is revolved through frictional contact of the two wheels 8 and 21, the screw impeller or spiral blade 10 is also revolved to lift or impel the water through the pipe connection to the radiator tank for causing circulation of water through the hereinbefore mentioned parts for the purpose of extracting heat from the engine cylinder. By the utilization of the cone shaped friction pulley wheel attachment 8 the pump device may readily be adjusted for use with the pulley 6 of the fan belt, and the pipe connection 2 may be substituted for existing pipe connections now in use on automobiles. For this purpose the original connection may be

removed and the pipe connection 2 which is made in standard sizes and shapes, may be substituted and bolted in proper place for conveying the water in circulation throughout the system. In this manner a circulation of water is positively accomplished regardless of weather conditions and the engines may be cooled as required.

Having thus fully described my invention, what I claim as new and desire to secure by Letters Patent is—

The combination with a grooved pulley having flanges of a friction cone, spaced attaching lugs on said cone for engagement with one of said flanges to form a rigid structure, a shaft having a suitable bearing, a friction wheel on said shaft and a friction rim on said wheel for contact with the friction cone.

In testimony whereof I affix my signature.

EDGAR B. HOOVER.
